UNITED STATES PATENT OFFICE

EDMOND DAVID CODDINGTON, OF EAST CLEVELAND, OHIO, ASSIGNOR TO THE FORESTEK PLATING & MFG. COMPANY, OF CLEVELAND, OHIO, A FIRM

DESIGN FOR A TOASTER OR SIMILAR ARTICLE

Application filed September 16, 1932. Serial No. 44,871. Term of patent 7 years.

To all whom it may concern:

Be it known that I, EDMOND DAVID CODDINGTON, a citizen of the United States, residing at East Cleveland, in the county of Cuyahoga and State of Ohio, have invented a new, original, and ornamental Design for a Toaster or Similar Article, of which the following is a specification, reference being had to the accompanying drawing, forming part thereof.

Fig. 1 is an elevational view of a toaster, showing my new design.

Fig. 2 is a side elevational view thereof, and,

Fig. 3 is a side elevational view, illustrating the toaster in an open position.

I claim:

The ornamental design for a toaster or similar article, as shown.

EDMOND DAVID CODDINGTON.
